UNITED STATES PATENT OFFICE.

WILLIAM J. BAUER, OF NEW YORK, AND FREDERICK O. WIERTH AND ABRAHAM S. MEADOFF, OF BROOKLYN, NEW YORK, ASSIGNEES TO QUEEN AUTOMATIC PHONOGRAPH CO., INC., OF NEW YORK, N. Y., A CORPORATION OF NEW YORK.

TONE MODULATOR FOR PHONOGRAHS.

Application filed March 24, 1921. Serial No. 454,981.

To all whom it may concern:

Be it known that we, WILLIAM J. BAUER, FREDERICK O. WIERTH, and ABRAHAM S. MEADOFF, citizens of the United States, and residents of New York and Brooklyn, respectively, in the counties of New York and Kings and State of New York, have invented certain new and useful Improvements in Tone Modulators for Phonographs, of which the following is a specification.

This invention relates to improvements in tone-modulator for graphophones, and more particularly to that type of modulator having movable elements for exerting various degrees of pressure on the vibratory transmitter bar of the sound box to control the amplitude of the vibrations, and the general object of the invention is to simplify the construction of the modulator and compactly arrange the units to admit of the modulator being easily applied to the sound box and the operative parts thereof conveniently and effectively operated. To this end the invention resides in the provision of a novel form of jaws for engaging the transmitter rod and a plate for supporting the jaws and novel and effective operating mechanism, carried by the plate for increasing or decreasing the pressure of the jaws on the transmitter rod.

Other objects will appear and be better understood from that embodiment of the invention of which the following is a specification, reference being had to the accompanying drawings forming a part thereof, in which:

Figure 1 is a side elevation of a sound box with the modulator attached thereto.

Figure 2 is a vertical sectional view taken through the sound box and a portion of the modulator.

Figure 3 is a vertical sectional view taken through the modulator and showing the latter in applied position.

Figure 4 is a rear elevation of the modulator detached from the sound box, and,

Figure 5 is a detail perspective view of one of the angular shaped links of the modulator and its companion transmitter bar engaging finger.

In the drawings the numeral 5 designates a sound box of ordinary construction having

the usual diaphragm 6 and the vibratory transmitter bar 7 connected to the diaphragm.

The modulator is designated in its entirety by the numeral 8 and comprises a supporting plate 9 which is of dish shape, as shown in Figure 2, and is mounted on the sound box 5, the peripheral flange of the plate serving to hold the body of the plate spaced from the sound box 5 and is secured to the sound box by means of screws 10. Openings 11 are formed in the plate so as to prevent the latter from dampening the tone. The plate is cut away at the lower edge thereof, as shown in Figures 1 and 2 to permit of the passage of the needle holder carried by the lower end of the transmitter bar 7.

A pair of L shaped or angular links 12, 70 are positioned within the plate 9 and have their short arms extending in opposite directions and terminally pivoted to the inner face of the peripheral flange of the plate. A rotatable disc 13 is positioned interiorly of the plate and is carried by one end of a shaft 14, that extends through the plate and is journaled therein, the outer end of the shaft having associated therewith a manipulating wheel 15. When the wheel 15 is turned motion will be imparted to the shaft 14 and the disc 13.

The disc 13 is provided with a pair of arcuate shaped cam slots 16, which are eccentric of each other and of the axis of the disc. 85 The upper ends of the long arms of the links 12 are terminally provided with laterally extending pins 17, which are slidably received by the slots 16 in the disc 13. When the disc is rotated in one direction, namely, in a clockwise direction, the pins 17 will be directed toward the inner ends of the slots 16 and effect movement of the long arms of the links 12 toward each other and contra-clockwise rotation of the disc will cause the long arms of the links to move away from each other.

A pair of downwardly converging fingers 18, formed preferably of spring metal, are positioned between the long arms of the links 12 and have their lower ends free and their upper ends terminally secured to the long arms of the respective links 12. The free ends of the fingers are adapted to engage the

vibratory transmitter bar 7 and their degree of pressure on the rod is regulated by the degree of inward movement given the long arms of the links 12. The inner faces of the fingers are covered with fibrous or rubber strips 19 to prevent injury to the bar 7.

When it is desired to modulate the sound vibrations the wheel 15 is rotated in a clockwise direction thereby similarly rotating the disc 13, with a resultant pressure of the fingers 18 on the bar 7, the rotation of the wheel being continued until the desired pressure is exerted on the bar, the tone softening as the pressure of the fingers increases.

From the foregoing it will have been observed that the construction of modulator described is of simple and compact construction, that it will effectively modulate the tone and that it can be conveniently applied to any sound box without reconstructing the latter.

Having thus described the invention, what is claimed as new is—

1. In a tone modulator for graphophones, a transmitter bar, a pair of resilient fingers adapted to engage the transmitter bar and means for controlling the engagement of said fingers and bar to vary the pressure of said fingers on said bar and to vary the extent of contact between said fingers and bar, so that said contact may vary from substantially a single point to substantially the entire length of the transmitter bar.

2. In a tone modulator for graphophones, a transmitter bar, means engaging the transmitter bar and second means adapted to vary the pressure of said first mentioned means on said bar and adapted further to vary the extent of contact between said first mentioned means and said bar, in such manner that said contact may vary from substantially a single

point to substantially the entire length of the transmitter bar.

3. A sound modulator for graphophones comprising a support adapted to be attached to the sound box, a rotatable element carried by said support, movable elements having one end thereof secured to the support and having their other end movably connected with the rotatable element, and transmitter bar engaging elements carried by said movable elements.

4. A sound modulator for graphophones including a support, a pair of transmitting bar engaging elements movably mounted on the support, a rotatable element carried by the support, and having cam slots therein and means carried by the movable elements and engaging in the slots and adapted to effect movement of the movable elements when the rotatable element is operated.

5. A sound modulator including a support, a pair of angular shaped elements each having one end secured to the support, transmitter bar engaging fingers carried by the angular shaped elements and means carried by the support for effecting movement of the angular shaped elements.

6. A sound modulator including a support, movable elements carried by the support, and each having one end secured to said support, operating means for the movable elements and carried by the support, and transmitter bar engaging fingers carried by the movable elements.

Signed at New York, in the county of New York and State of New York, this 5th day of March A. D. 1921.

WILLIAM J. BAUER,
FREDERICK O. WIERTH,
ABRAHAM S. MEADOFF.
